METHOD OF PRODUCING SEALED CRYSTAL LAYERS IN BOTTLES

Frank Prochazka, Cicero, Ill.

Application November 16, 1935, Serial No. 50,247

4 Claims. (Cl. 91—68)

My invention is directed to a novel method or process of forming a crystal coated surface upon the inner surfaces of transparent containers such as bottles or the like which are particularly adapted for use in the sale of whiskies known as rock and rye in combination with means and methods for binding said crystals together and coating the exposed surfaces thereof with a substance such as paraffin or its known equivalents, which substances are impervious to whiskey or other liquid and which have no undesirable reaction in contact therewith.

Heretofore it has been known in the art of rectification and manufacture of liquors that crystals may be formed and caused to adhere to some extent to the inner surface of a glass bottle, and such crystal formation has to a considerable extent been practiced with the undesirable result that the liquids placed into the bottle (where whiskies or liqueurs are not fully saturated with sugar and sugar syrup), will "absorb" or dissolve the crystals formed in the bottle. As stated, the past practice for many years has failed to evolve a method and means to eliminate either the dissolution of the crystals formed on the bottle wall, or the undesirable action of the liquid in breaking the bond or adhering tendency of the crystals themselves to the bottle wall which have resulted in the disappearance or falling down to the bottom of the bottle of the crystal formation on the inner surface of the bottle. Furthermore, recent demands in the trade indicate desire for so-called rock and rye whiskey which is of a sugar syrup content considerably less than the fully saturated rock and rye known in the past, and in many instances, for a whiskey of relatively high alcoholic content with lower sugar syrup content. A further demand is for a package for such product which will show for long periods of time the proper crystal formation visible through the glass walls. With heretofore known methods fulfillment of these demands is impossible for reasons heretofore stated.

Accordingly, it is an important object of my invention to provide a method and process consisting of a combination of steps of not only forming the inner coating or layer of adherent crystals in the container, but also to provide a coating to the sugar crystal layer which will act to further bind said crystals together, to hold the same in position and to protect the same and maintain the same out of contact with the alcoholic liquid contents of the bottle which otherwise would have the undesirable effects stated hereinbefore.

A further object of my invention is the provision of a transparent container such as a bottle for liquors of relatively high alcoholic content having adjacent the inner surface thereof first a layer of syrup; thence thereupon a layer of sugar crystals of various irregular sizes and shapes and thence a layer of a water impervious composition such as paraffin or its known equivalents which will protect the crystal layer from the action of the liquid contents and hold said crystal layer in proper position to present a desirable uniformly crystallized inner surface for the bottle plainly visible from the outside.

Other and further objects of my invention will be apparent from the following description and claims.

This invention (in a preferred form) is illustrated in the drawing and hereinafter more fully described.

On the drawing:

Fig. 1 is a side elevational and partially cross sectional view of a typical glass bottle container with parts broken away to show the inner layers formed along the inside wall.

Fig. 2 is an enlarged fragmentary view showing a segment of the bottle wall with only a coating of syrup applied thereto.

Fig. 3 is an enlarged fragmentary view showing in cross section a typical view of the container wall after the application of crystals.

Fig. 4 is an enlarged fragmentary view showing a cross section of the finished superposed layers.

Referring to the drawing, the reference numeral 10 indicates a bottle which may be of any convenient size or shape and preferably made of clear glass having its upper end terminating in a suitable neck which has thereon a threadingly engaged screw cap 11.

The first step in the practice of my invention is to pour into a glass container a sufficient amount of sugar syrup of substantially gluey consistency sufficient to be distributed upon the entire inner surface of the bottle by proper rotation and movement of the bottle, the surplus syrup not adhering to the walls being preferably poured off. This step forms a relatively thin syrup layer 12, as shown in the enlarged fragmentary view of Fig. 2.

The next step is to apply and evenly distribute sugar crystals upon the entire inner surface so that the same adhere and contact the gluey syrup coating 12. I have found this can be satisfactorily performed by placing into the bottle approximately two ounces of sugar crystals or preferably crystal rock candy in a form sufficiently broken and divided so that the same do not vary too

greatly in size, and being preferably of a size within the ranges indicated in the enlarged fragmentary view in Fig. 3. In the drawing, the reference numeral 13 indicates the rock candy crystals, 5 which after being placed in the bottle are caused to be substantially evenly distributed upon the entire inner syrup coating 12 by rotation and movement of the bottle. The bottle with the syrup coating and adherent crystals is then set 10 aside and allowed to dry and harden for a period of about two weeks, after which time the syrup is relatively hard and the crystals dry.

The next step consists of applying and evenly distributing a paraffin coating to the entire interior surfaces of both the crystals 13 and so much of the syrup coating 12 as may remain exposed between the various adjacent crystals. I found that this may be satisfactorily applied by pouring into the bottle a sufficient quantity, preferably a full bottle, of hot melted paraffin preferably at a temperature of between 160° and 170° F. When the hot thin paraffin comes in contact with the inner surfaces of the crystals 13 and such exposed surfaces of the syrup coating 12 as may remain between the various crystals, the paraffin immediately begins to harden around such crystals and between the same and thereby the crystals 13 are completely surrounded and sealed with semi-hard paraffin to form the sealing coating 14 indicated in the enlarged cross sectional view of Fig. 4, this coating 14 filling up entirely the various irregularly shaped spaces between the crystals as well as adhering to all the exposed surfaces of the crystals which project from the syrup coating 12. While this is going on and while the main part of the hot paraffin is still liquid, I drain the bottle of the liquid paraffin, thereby leaving the crystals 13 completely enveloped and sealed within the coating 14 which upon further setting will harden to the normal hardness of dry paraffin. It will be understood that this paraffin coating 14 acts to hold the crystals in the position which they have taken when coming in contact with the syrup coating to thereby prevent dislodgement and falling of the same to the bottom of the bottle as well as forming a liquid impervious coating about the crystal surfaces. As indicated in Figs. 1 and 4 the inner surface of the paraffin coating 14 is quite irregular in shape due to the various sizes, shapes and degree of projection of the various crystals.

The paraffin and syrup coatings or liners formed as above indicated with the contained 55 crystals readily produce a semi-transparent package, namely of sufficient transparency to see the normally darker whiskey contents of the bottle. To a viewer of the exterior of the bottle the crystals are quite bright and have their normal appearance, this producing a very desirable appearing package which produces the crystal-coated wall and package. The glass container, to the inner walls of which rock candy crystals have been applied in the manner aforescribed, will last 60 an indefinite length of time and the crystals will not, without manual force, break away or fall to

the bottom of the bottle to thereby expose and render completely transparent some particular area which action would create an undesirable appearance of the bottle and package as a bottle. This also eliminates the heretofore expressed 5 difficulty incident to the dissolution of the sugar crystals by the liquor which consequently changes the alcoholic content or proportion of the liquor as a whole, and likewise eliminates the possibility of any change in the sugar or sugar syrup content 10 of the whiskey which also has been a heretofore unsolved difficulty where crystals were dissolved by the liquid contents.

I am aware that numerous details of construction may be varied and likewise that various steps 15 of the process may be varied through a wide range without departing from the principles of this invention, and I therefore do not desire to limit the patent granted hereon otherwise than necessitated by the prior art. 20

I claim as my invention:

1. In a process of coating the interior of a liquid container, the steps of first applying to the interior of the container a syrup of gluey consistency in a relatively thin layer; thence placing sugar 25 crystals into said bottle and distributing same over substantially the entire inner surface so that the same will adhere to said syrup; allowing the syrup and crystals to dry and harden; and thence applying molten paraffin to the inner surfaces of 30 said crystal coating and allowing said paraffin to harden.

2. The process of forming adjacent superposed layers of sugar crystals and paraffin upon the interior of a bottle consisting of placing into the 35 bottle syrup of a gluey consistency, pouring the excess syrup therefrom; thence applying sugar crystals to substantially the entire inner surface of said bottle and in contact with said syrup; and thence sealing said crystals in said bottle and together by applying melted paraffin thereto and allowing said paraffin to solidify. 40

3. The process of forming adjacent superposed layers of sugar crystals and paraffin upon the interior of a bottle consisting of placing into the 45 bottle syrup of a gluey consistency, pouring the excess syrup therefrom; thence applying sugar crystals to substantially the entire inner surface of said bottle and in contact with said syrup; thence placing hot paraffin into said bottle and 50 allowing it to stand a relatively short time and thence pouring the surplus paraffin from within the bottle, thereby permitting the paraffin to form a semi-solid coating over said crystal layer.

4. In a process of coating the interior of a liquid container, the steps of first applying to the interior of the container a syrup of gluey consistency in a relatively thin layer; thence placing sugar 55 crystals into said bottle and distributing same over substantially the entire inner surface so that the same will adhere to said syrup; and thence applying molten paraffin of approximately 160° to 170° F. to the inner surfaces of said crystal coating and allowing said applied materials to harden. 60
